Inventor:

C. B. Dickinson

United States Patent Office.

CHARLES B. DICKINSON, OF BROOKLYN, NEW YORK.

Letters Patent No. 78,192, dated May 26, 1868; antedated May 18, 1868.

COMBINED ARM-REST AND PAPER-CUTTER.

The Schedule referred to in these Letters Patent and making part of the same.

TO ALL WHOM IT MAY CONCERN:

Be it known that I, CHARLES B. DICKINSON, of Brooklyn, in the county of Kings, and State of New York, have invented, made, and applied to use a certain new and useful Combined Arm-Rest and Paper-Cutter; and I do hereby declare the following to be a full, clear, and exact description of the said invention, reference being had to the annexed drawing, making part of this specification, wherein—

Figure 1 is a plan of the said improvements in the position of an arm-rest.

Figure 2 is a side view of the same as applied to a book; and

Figure 3 is a plan of the article as folded and adapted to use as a paper-cutter, or as a ruler.

Similar letters denote the same parts.

Heretofore, a long piece of thin sheet metal has been employed as a paper-cutter, or edge against which paper can be torn, and accountants and others have had an arm-rest made of a thin piece of wood to slip into the book, and with a thicker portion at the bottom, outside the book, forming an arm-rest to facilitate writing near the bottom of the page.

These arm-rests generally are large, and cumbersome for the contracted space of a desk, and cannot be used for anything else.

The nature of my said invention consists in a combined paper-cutter and arm-rest, that can be used for either purpose very readily, or may be used also as a ruler. The said article can also be folded so as to occupy but little more space than an ordinary paper-cutter.

In the drawing, *a* represents a thin-metallic plate, that should have a hole at *b*, so as to hang up, the metal being of sufficient width, length, and stiffness to answer the desired purpose.

c is the arm-rest, formed of wood or other suitable material. The arm-rest *c* and paper-cutter *a* are connected by a screw or rivet at *d*, upon which the parts can turn so that the paper-cutter may stand at right angles, or nearly so, for insertion between the leaves of a book, to sustain the arm-rest at the foot of the page, or the cutter may be turned so as to coincide, or nearly so, with the arm-rest, as seen in fig. 3.

The paper-cutter *a* may be used as a cutter or straight-edge for tearing paper when in either of the position shown; but when in the position shown in fig. 3, it will be the most convenient, as the arm-rest stiffens the paper-cutter.

The edge *e e* of the rest *c* forms a good ruler, and, being bevelled, as shown in fig. 2, prevents the ink blotting by running under the edge of the ruler.

My aforesaid article is very cheap, strong, compact, and eminently adapted to the use of book-keepers and others.

What I claim, and desire to secure by Letters Patent, is—

The combined arm-rest and paper-cutter, made substantially as and for the purposes set forth.

In witness whereof, I have hereunto set my signature, this twenty-second day of October, A. D. 1867.

C. B. DICKINSON.
